UNITED STATES PATENT OFFICE

139,404

DESIGN FOR A MILLING MACHINE

Robert S. Condon, Rutland, Vt.

Application August 11, 1944, Serial No. 114,832

Term of patent 7 years

(Cl. D54—14)

To all whom it may concern:

Be it known that I, Robert S. Condon, a citizen of the United States, residing at Rutland, county of Rutland, State of Vermont, have invented a new, original, and ornamental Design for a Milling Machine, of which the following is a specification, reference being had to the accompanying drawings, forming a part thereof.

In the drawings:

Fig. 1 is a front elevation of a milling machine showing my new design.

Fig. 2 is an elevational view of one side thereof.

Fig. 3 is an elevational view of the other side thereof.

Fig. 4 is a rear elevational view thereof.

Fig. 5 is a top plan view thereof.

I claim:

The ornamental design for a milling machine, substantially as shown.

ROBERT S. CONDON.
